UNITED STATES PATENT OFFICE.

HARRY W. YOUNG, OF WHITEHALL, MICHIGAN.

RUDDER-POST BEARING.

1,287,167.

Specification of Letters Patent. Patented Dec. 10, 1918.

Application filed April 30, 1917, Serial No. 165,468. Renewed April 27, 1918. Serial No. 231,276.

To all whom it may concern:

Be it known that I, HARRY W. YOUNG, a citizen of the United States, residing at Whitehall, in the county of Muskegon and 5 State of Michigan, have invented new and useful Improvements in Rudder-Post Bearings, of which the following is a specification.

This invention relates to ships' rudders in 10 which the rudder shaft or post is mounted in a bearing tube, and the invention relates more particularly to this tube, the object being to provide a novel and improved supporting means therefor which enables it to 15 be set vertically irrespective of the angle of the vessel's bottom.

The object stated is attained by means of a combination and arrangement of parts to be hereinafter described and claimed, and 20 in order that the same may be better understood, reference is had to the accompanying drawing forming a part of this specification.

In the drawing—

Figure 1 is a longitudinal section showing 25 the application of the invention;

Fig. 2 is an inverted plan view thereof; and

Fig. 3 is a longitudinal section showing a slight modification.

Referring specifically to the drawing, 5 denotes the bottom of a boat at the stern thereof, and 6 shows a fragment of the shaft or post which carries the rudder. This rudder shaft or post is supported in a bearing 30 tube 7 positioned vertically in an opening in the boat bottom and depending a suitable distance therefrom. On the boat bottom is secured a housing 8 which incloses the depending portion of the rudder shaft. This 35 housing has an oval base outline and is gradually tapered to frusto-conical form, the contracted portion of the housing having an internal seat 9 for an abutment 10 mounted on the bearing tube. This abutment is substantially semi-spherical and the 40 seat is correspondingly formed, in view of which a ball-and-socket or flexible joint is

had between the housing and the bearing tube inclosed therein. On the bearing tube, above the boat bottom is threaded a nut 11 50 by which the tube may be drawn upward to firmly hold the abutment on the seat, thereby preventing leakage of water into the housing. By the ball-and-socket joint, the bearing tube can be readily positioned vertically irrespective of the angle or slope of the boat bottom. 55

Fig. 3 shows a slightly modified structure, the ball-and-socket joint being inverted. Otherwise, the structure is the same as the 60 first described one.

I claim—

1. The combination with the bottom of a boat and a rudder post bearing tube depending therefrom; of a housing mounted on the 65 boat bottom and inclosing the depending bearing tube, and a ball-and-socket connection between the housing and the bearing tube.

2. The combination with the bottom of a 70 boat and a rudder post bearing tube depending therefrom; of a housing mounted on the boat bottom and inclosing the depending bearing tube, and a flexible connection between the housing and the bearing tube. 75

3. The combination with the bottom of a boat and a rudder post bearing tube depending therefrom; of a housing mounted on the boat bottom and inclosing the depending bearing tube, said housing having a curvilinear seat, and a correspondingly shaped abutment on the bearing tube engaging said seat. 80

4. The combination with the bottom of a boat and a rudder post bearing tube depending therefrom; of a housing mounted on the boat bottom and inclosing the depending bearing tube, said housing having a curvilinear seat, and a correspondingly shaped abutment on the bearing tube engaging said 85 seat, and means for clamping said abutment to the seat. 90

In testimony whereof I affix my signature.
HARRY W. YOUNG.
